UNITED STATES PATENT OFFICE.

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS.

CURTAIN-FIXTURE.

1,349,041.

Specification of Letters Patent. Patented Aug. 10, 1920.

Application filed February 18, 1920. Serial No. 358,474.

To all whom it may concern:—

Be it known that I, JAMES H. BOYE, a citizen of the United States, residing at Chicago, county of Cook, and State of Illinois, have invented certain new and useful 5 Improvements in Curtain-Fixtures, of which the following is a specification.

This invention relates to the general art of curtain fixtures, and has reference more 10 particularly to improvements in curtain rods or hangers designed to support a single curtain, or a curtain with one or more over-drapes, side-drapes, etc., in proper position to cover a window or other opening. A 15 leading object of the invention is to provide an improved construction of curved-end curtain rod and end supporting bracket therefor, by the use of which a uniform or unit size and shape of two-piece telescoping flat curtain rod may be used in the assembling of complete fixtures of any required lengths designed to support a plurality of curtains or a curtain and one or more over-drapes, and requiring from two 20 to six individual rods. Other objects of 25 the invention are, to provide an improved supporting bracket for the end of the rod, to provide an improved intermediate bracket 30 for use on wide or double windows requiring a pair of curtains, to provide, in combination with the end and intermediate brackets, improved means for mounting and removably locking the ends of the rod in said brackets, and generally, to provide an improved 35 curtain fixture of the character specified, characterized by economy of manufacture, ease and interchangeability in assembling, neatness of appearance, and a high degree of strength and rigidity in service.

40 With these and other objects in view, which will be apparent from the following detail description, the invention consists of the matter hereinafter described, typically illustrated in the drawings, and defined as 45 to subject matter and scope in the appended claims.

Referring to the drawings:—

Figure 1 is a top plan view, illustrating my invention as embodied in a structure designed to serve a narrow or single window;

Fig. 2 is a view similar to Fig. 1, showing the invention embodied in a structure employing an intermediate supporting bracket for the curtain rod and adapted to serve a wide or double window; 55

Fig. 3 is a top plan view of one of the end brackets;

Fig. 4 is a front elevation of the bracket shown in Fig. 3;

Figs. 5 and 6 are sectional views taken on 60 the lines 5—5 and 6—6 of Fig. 4;

Fig. 7 is a detail view of the elbow-shaped outer end portion of the outer rod section, partly in longitudinal section, and illustrating the adjustable fastening device mounted 65 therein;

Fig. 8 is an outside-elevation of the curved outer end portion of the outer rod section, as viewed from the right of Fig. 7;

Fig. 9 is a top plan view of the intermediate supporting bracket shown in Fig. 2; 70 and,

Fig. 10 is a sectional view on the line 10—10 of Fig. 9.

Referring first to the form of the invention illustrated in Fig. 1, wherein are shown a pair of spaced extensible rods of the flat telescoping type adapted to be supported at their outer ends only by brackets on the window casing, 11 designates the over rod section having a curved or elbow-shaped outer end portion 12 and a straight inner end, and 13 designates the inner rod section similarly formed with an elbow-shaped outer end portion 14 and a straight inner 80 end that telescopes within the inner end of the over rod section 11. In Fig. 1 a pair of such telescoping rods are shown, the inner rod designed to carry the curtain and outer rod to carry an over-drape; and it will be 85 observed that the two over rod sections 11 are identical in size and shape, and the two inner rod sections 13 are likewise identical in size and shape.

In order that the two rods, composed of 90 corresponding identical parts or sections, may be mounted in the spaced relation shown, I have designed end brackets therefor of a special character designed to support and removably lock in place the curved 95 100

or elbow ends of the two rods which are of equal lengths. This supporting bracket is illustrated in detail in Figs. 3 to 6 inclusive, and comprises a base plate 15 formed with holes 16 to receive attaching screws, and further formed on its upper edge with relatively short and long forwardly projecting lips 17 and 18 and on its lower edge with relatively short and long forwardly projecting lips 17' and 18', the lip 17' lying directly below the lip 17 and the lip 18' lying directly below the lip 18. These lips are transversely curved or channel shaped in cross-section, as shown in Fig. 4, to fit the rounded upper and lower edges of the rod, and the lips 17 and 17' are formed with longitudinal slots 19 and 19' respectively, and the lips 18 and 18' are similarly formed with longitudinal slots 20 and 20' respectively. The lips 17, 17' with their longitudinal slots 19, 19' together form a socket to support and removably lock in place the elbow end of the inner curtain rod; and the longer lips 18, 18' with their longitudinal slots 20, 20' constitute a similar socket to support and removably lock in place the elbow end 12 of the outer or drape rod.

Referring to Figs. 7 and 8, within the hollow end of each elbow portion of the rod is inserted a fastening member of a T-form comprising a flat shank 21, and a projecting head 22. The upper and lower ends of the head 22 lie within the upper and lower slots respectively of the lips of the bracket, the rod being inserted by canting it upwardly and first entering the lower end of the head 22 in the outer end of the lower and longer slot 19' or 20', and then pushing it inwardly until the upper end of the head passes into the upper slot 19 or 20, and then restoring the rod to normal position. In the assembled position, the longer lower lip 17' or 18' forms a rest or support for the curved end of the rod, while the upper lip 17 or 18 serves as an abutment or brace to hold the rod against tilting under the weight of the curtain or drape, and the engagement of the upper end of the fastener 22 in the upper slot prevents the rod from being drawn out of the socket, except by reversing the entering movement. Preferably, as shown in Figs. 7 and 8, the connecting member 21 is adjustable lengthwise, being formed with a protuberance 23 adapted to snap into either of a pair of spaced holes 24 and 25 formed in the side wall of the rod. This is to permit the rod to be mounted at a greater distance from the window casing where it may be necessary to clear a curtain roller or other window fixture.

In Figs. 2, 9, and 10, I have illustrated an embodiment of the same principle as applied to a wide or double window fixture requiring an intermediate supporting bracket.

Here I employ, on either side of the intermediate bracket, the same over rod sections 11 with curved elbow ends 12, and the same end brackets shown in Fig. 1 and hereinabove described; and in association with the, 75 over rod sections 11, I employ straight inner telescoping sections 26, which may be of equal lengths, and the inner ends of which are equipped with T-shaped attaching members 27, best shown in Fig. 10. The intermediate supporting bracket is a U-shaped member comprising parallel sides 28, attaching feet 29 and, at its outer end, a cross connecting member or head 27. In the sides 28 are formed a number of vertical 80 spaced slots 31, into which the necks of the T-shaped fasteners 27 are entered, in the manner clearly shown in Figs. 9 and 10. By this means the inner ends of the rods are strongly supported upon and locked to 85 the intermediate bracket against pulling out endwise, being removable only by a lifting operation.

It will be observed that the sockets of the end brackets are spaced apart a distance 90 substantially equal to the spacing of the main longitudinal portions of the rods, so that the two rods lie substantially parallel and equally spaced throughout their entire extent. The chief object, however, of the described construction resides in the fact that a single pair of over and inner rod sections consisting, in the structure of Fig. 1, of the rod sections 11 and 13, and in the structure of Fig. 2 of the rod sections 11 and 26, may 100 serve as a manufacturing unit for single, double, or triple rod assemblies, entirely eliminating the necessity of providing rods or rod sections of different lengths to carry the curtain and the drape or drapes. Furthermore, with the described attachment devices in the ends of the rods, the latter are reversible and invertible in either the narrow construction shown by Fig. 1 or the wide construction shown by Fig. 2. A further advantage in employing a multiple piece rod with one end curved to form the elbow and the other end straight, is that thereby a curved end rod adjustable to any 110 desired length can be made, by simply inserting between two curved end rod sections a number of telescoping straight sections until the desired or required length is found.

I claim—

1. In a curtain fixture, the combination 120 with a pair of spaced parallel curtain rods having inwardly curved end portions of equal lengths, of a supporting bracket having an attaching base and a pair of sockets to receive said curved end portions of the 125 rods, said sockets being spaced at different distances from said base.

2. In a curtain fixture, the combination 130 with a pair of spaced parallel curtain rods having inwardly curved end portions of

equal lengths, of a supporting bracket having sockets to receive said curved end portions of the rods, said sockets being spaced apart both forwardly and laterally a distance substantially equal to the distance between the main portions of said rods.

3. In a curtain fixture, the combination with duplicate inside and outside rod sections for carrying a curtain and an over-drape respectively, each of said rod sections having an integral elbow-shaped end portion, of a supporting bracket having receiving sockets for said elbow-shaped end portions which are spaced apart both forwardly and laterally a distance substantially equal to the distance between the main portions of said rods.

4. In a curtain fixture, a pair of flat two-piece telescopic curtain rods, each comprising an over-rod section formed with an elbow-shaped end and a straight inner rod section, the corresponding sections of the two rods being duplicates of each other, in combination with a bracket having forwardly and laterally spaced sockets to receive and hold the elbow-shaped ends of said rods, and a bracket having forwardly and rearwardly spaced sockets to receive and hold the straight ends of said rods.

5. In a curtain fixture, the combination of a flat hollow curtain rod having an inwardly curved end, a fastening member inserted in said end and having upper and lower projections, and a supporting bracket formed with forwardly projecting upper and lower lips between which said inwardly curved end of the rod is received, said lips having openings to receive the projections of said fastening member.

6. In a curtain fixture, the combination of a flat curtain rod having an inwardly curved end, a fastening member adjustable inwardly and outwardly of said curved end and formed with upper and lower projections, and a supporting bracket formed with forwardly projecting lips between which said inwardly curved end of the rod is received, said lips having openings to receive the projections of said fastening member.

7. In a curtain fixture, the combination of a flat curtain rod having an inwardly curved end, upwardly and downwardly projecting fastening lugs on said end, and a supporting bracket formed with forwardly projecting upper and lower lips between which said inwardly curved end of the rod is received, said upper lip having an opening to receive said upwardly projecting fastening lug, and said lower lip being longer than said upper lip and having a longitudinal slot to receive said downwardly projecting fastening lug.

8. In a curtain fixture, the combination

of a flat hollow curtain rod having an inwardly curved end, a fastening member inserted in said end and having upper and lower projections, and a supporting bracket formed with forwardly projecting upper and lower lips between which said inwardly curved end of the rod is received, said upper lip having an opening to receive the upper projection of said fastening member, and said lower lip being longer than said upper lip and having a longitudinal slot to receive the lower projection of said fastening member.

9. In a curtain fixture, the combination of a pair of duplicate flat hollow curtain rods each having an elbow-shaped end, of fastening members inserted in said ends and each having upper and lower projections, and a supporting bracket formed with laterally spaced pairs of longitudinally slotted upper and lower lips between which the elbow-shaped ends of said rods are received, the slots of the outer pair of said lips lying forwardly of the slots of the inner pair.

10. In a double curtain fixture, an intermediate rod-supporting member comprising a U-shaped bracket adapted to be secured at its open end to a window casing and having formations in its side walls adapted to receive and support the ends of curtain rods on either side thereof.

11. In a double curtain fixture, an intermediate rod-supporting member comprising a U-shaped bracket adapted to be secured at its open end to a window casing and having vertical slots in its side walls adapted to receive and support the ends of curtain rods on either side thereof.

12. In a double curtain fixture, an intermediate rod-supporting member comprising a U-shaped bracket adapted to be secured to a window casing and having slots in its side walls, in combination with flat curtain rods, and fastening means on the inner ends of said rods adapted to enter the slots of said bracket and lock said rods against withdrawal endwise.

13. In a double curtain fixture, an intermediate rod-supporting member comprising a U-shaped bracket adapted to be secured at its open end to a window casing and having slots in its side walls, in combination with hollow flat curtain rods, and T-shaped fastening members inserted in the inner ends of said rods and adapted to enter the slots of said bracket and lock said rods against withdrawal endwise.

14. In a double curtain fixture, the combination of end brackets each having a pair of forwardly and laterally spaced sockets, an intermediate bracket having a pair of parallel vertical side walls formed with slots, and two pairs of curtain rods, the rods of each pair having inwardly curved end por-

tions supported in the sockets of said end brackets and straight end portions supported in the slots of said intermediate bracket.

15. In a double curtain fixture, the combination of end brackets each having a pair of forwardly and laterally spaced sockets, an intermediate bracket having a pair of parallel vertical side walls formed with

vertical slots, and two pairs of duplicate flat telescopic curtain rods, the rods of each 10 pair having elbow-shaped end portions supported in the sockets of said end brackets and straight end portions supported in the vertical slots of said intermediate bracket.

JAMES H. BOYE.
